(57) CLAIM

The ornamental design for a portion of a shoe upper, as shown and described.

DESCRIPTION

FIG. 1 is a perspective view of a portion of a shoe upper showing my new design;

FIG. 2 is a second perspective view thereof; and,

FIG. 3 is a side view thereof.

The uneven broken lines immediately adjacent to the shaded area represent unclaimed boundaries of the design. The broken line showing of generally circular features within the shaded area and the uneven broken line showing of the remainder of the shoe are for illustrative purposes only and form no part of the claimed design.
